CASING FOR A PORTABLE ELECTRIC HEATER

Frank B. Roth, Clayton, Mo., assignor to Atlas Tool & Manufacturing Co., St. Louis, Mo., a corporation of Missouri

Filed Jan. 2, 1962, Ser. No. 68,150

Term of patent 14 years

(Cl. D81—10)

FIG. 1 is a top plan view of a casing for a portable electric heater embodying my new design;

FIG. 2 is a front perspective view thereof; and

FIG. 3 is a side view thereof.

The back of the casing hereof is plain.

I claim:

The ornamental design for a casing for a portable electric heater, substantially as shown and described.
